CLAIM

The ornamental design for a call blocking device, as shown and described.

DESCRIPTION

FIG. 1 is a perspective view of a call blocking device, showing a first embodiment of my new design;

FIG. 2 is a top view thereof;

FIG. 3 is a left side view thereof;

FIG. 4 is a bottom view thereof;

FIG. 5 is a right side view thereof;

FIG. 6 is a front view thereof;

FIG. 7 is a rear view thereof;

FIG. 8 is a perspective view of a call blocking device, showing a second embodiment of my new design;

FIG. 9 is a top view thereof;

FIG. 10 is a left side view thereof;

FIG. 11 is a bottom view thereof;

FIG. 12 is a right side view thereof;

FIG. 13 is a front view thereof; and,

FIG. 14 is a rear view thereof.

The broken lines in the drawings depict portions of the call blocking device that form no part of the claimed design.

1 Claim, 12 Drawing Sheets
